UNITED STATES PATENT OFFICE

2,077,306

FOOD HANDLING APPARATUS

Sylvan Braun, Philadelphia, Pa., assignor to The Enterprise Manufacturing Company of Pennsylvania, Philadelphia, Pa., a corporation of Pennsylvania

Application February 13, 1936, Serial No. 63,814

8 Claims. (Cl. 226—38)

This invention relates to new and useful improvements in food handling apparatus and more particularly to feeding trays and the like therefor.

5 The principal object of the present invention is to provide a device of the character set forth which may be readily detached for cleaning and other purposes.

Another object of the invention is to provide a 10 device of the stated character which is of simple, rugged construction and relatively inexpensive to manufacture.

15 A further object of the invention is to provide a device of the character set forth which may be employed in conjunction with food handling apparatus now in use.

These and other objects of the invention and the details of construction thereof are set forth hereinafter and shown in the accompanying 20 drawing, in which:

Fig. 1 is a view in perspective of a feeding tray embodying the present invention; and

Fig. 2 is a fragmentary view in vertical section showing the feeding tray associated with apparatus for handling food stuffs.

25 Referring now more particularly to the drawing, reference numeral 1 designates generally a feeding tray of the customary type used in conjunction with food handling apparatus and having the usual side walls 2 and outlet opening 3 located centrally in the bottom thereof. The portion of the tray 1 through which said opening 3 extends is relatively thick as indicated at 4 and two or more suitably located holes 5 are 30 drilled or otherwise formed therein from the underside of said tray, said holes 5 being internally threaded as at 6 to receive bolts or the like 7.

In accordance with the invention, an annular 35 gasket, washer or like member 8 having apertures or openings 9 suitably located therein is positioned at the under side of the thicker portion 4 of the tray 1 surrounding the outlet opening 3 in the latter in such manner that the 40 previously mentioned bolts or the like 7 pass through said openings 9 in the gasket or washer member 8. The bolts 7 are also arranged to extend through suitably formed openings or holes 10 in a flange 11 which projects laterally from the 45 upper end of a tubular sleeve 12, and the tray 1 and gasket or washer 8 as well as said sleeve 12 are secured together by means of nuts or the like 13 threaded on the outer extremities of said bolts 7.

50 The inner diameter of the annular gasket or

washer member 8 and sleeve 12 are substantially equal to the diameter of the outlet opening 3 in the tray 1 and the external diameter of said sleeve 12 is substantially equal to the internal diameter of the inlet or neck 14 of a food handling apparatus so that the former will fit more or less snugly within the latter. It will be observed that the bolts 7 previously described are of such length that they extend an appreciable distance beyond the outer faces of the nuts or the like 13 threaded thereon and are arranged to removably engage suitably located recesses or openings 15 in the upper annular face of a flange 16 which projects laterally from the upper end of the neck or inlet 14 to the apparatus when 55 the sleeve 12 is inserted inwardly of said neck or inlet 14, to feed foodstuffs through the latter to the handling apparatus from the tray 1.

By constructing a feeding tray or the like in accordance with the foregoing description it will be obvious that such a tray may be readily attached to and removed from the inlet or neck of food handling apparatus for cleaning or other purposes, and that when associated with such apparatus with the bolts 7 inserted in the recesses or openings 15, relative rotation of the tray with respect to said neck or inlet is prevented.

It will be obvious that in the handling of certain types of foodstuffs, the gasket or washer member 8 may be found unnecessary and therefore can be eliminated and although a specific embodiment of the invention has been set forth for descriptive purposes it is not intended that said invention be precisely limited thereto but that changes and modifications in the detailed construction thereof may be incorporated where within the scope of the annexed claims.

I claim:

1. A feeding tray for use with food handling apparatus having an inlet neck portion and recesses laterally adjacent the inlet end thereof, said tray comprising a tubular sleeve member arranged for removable insertion inwardly of said inlet neck portion, a tray member having an outlet opening therein, means extending through openings in a portion of said sleeve member and secured in said tray member, and means engaging the first mentioned means to detachably connect the sleeve and tray members together, said first mentioned means extending a substantial distance beyond the second mentioned means and arranged for removable engagement with the recesses adjacent the inlet end of the neck portion to prevent relative rotation of said feeding tray 55

with respect to said neck portion when the sleeve member is inserted inwardly of the latter.

2. A feeding tray for use with food handling apparatus having an inlet neck portion and recesses laterally adjacent the inlet end thereof, said tray comprising a flanged tubular sleeve member arranged for removable insertion inwardly of said inlet neck portion, a tray member having an outlet opening therein, means extending freely through the flange of said sleeve member and secured in said tray member, and means engaging the first mentioned means to detachably connect the sleeve and tray members together, said first mentioned means extending 15 a substantial distance beyond the second mentioned means and arranged for removable engagement with the recesses adjacent the inlet end of the neck portion to prevent relative rotation of said feeding tray with respect to said neck portion when the sleeve member is inserted inwardly of the latter.

3. In a device of the character described, the combination with a food handling apparatus including an inlet neck portion having recesses 25 laterally adjacent the inlet end thereof, of a feeding tray, said feeding tray comprising a tubular sleeve member removably inserted inwardly of said inlet neck portion and having a flange at its outer end provided with openings therein, a tray 30 member having an outlet opening therein, means secured in said tray member and extending freely through the openings in the flange of said sleeve member when the latter is in substantial register with the outlet opening in the tray member, and 35 means engaging the first mentioned means to detachably connect said sleeve and tray members together, said first mentioned means extending a substantial distance beyond the second mentioned means and removably engaging the recesses adjacent the inlet end of the neck portion to prevent relative rotation of said tray with respect to said neck portion.

4. In a device of the character described, the combination with a food handling apparatus including an inlet neck portion having recesses laterally adjacent the inlet end thereof, of a feeding tray, said feeding tray comprising a tubular sleeve member removably inserted inwardly of said inlet neck portion, a tray member having an 45 outlet opening therein, means secured in said tray member and extending freely through a portion of said sleeve member when the latter is in substantial register with the outlet opening in the tray member, and means engaging the first mentioned means 50 to detachably connect said sleeve and tray members together, said first mentioned means extending a substantial distance beyond the second mentioned means and removably engaging the recesses adjacent the inlet end of the 55 neck portion to prevent relative rotation of said tray with respect to said neck portion.

5. A feeding tray for use with food handling apparatus having an inlet neck portion and recesses laterally adjacent thereto, said feeding tray comprising a sleeve member arranged for removable insertion inwardly of said inlet neck portion and a tray member having an outlet opening therein, and means extending through said sleeve member and secured in said tray member to detachably connect the sleeve and tray members together, said means projecting below the bottom of the tray member for removable engagement with the recesses adjacent the inlet end of the neck portion to prevent relative rotation of said feeding tray with respect to said neck portion when the sleeve member is inserted inwardly of the latter.

6. A feeding tray for use with food handling apparatus having an inlet neck portion and recesses laterally adjacent thereto, said feeding tray comprising a flanged sleeve member arranged for removable insertion inwardly of said inlet neck portion and a tray member having an outlet opening therein, and means extending through the flange of said sleeve member and secured in said tray member to detachably connect the sleeve and tray members together, said means projecting below the bottom of the tray member for removable engagement with the recesses adjacent the inlet end of the neck portion to prevent relative rotation of said feeding tray with respect to said neck portion when the sleeve member is inserted inwardly of the latter.

7. In a device of the character described, the combination with a food handling apparatus including an inlet neck portion having recesses laterally adjacent thereto, of a feeding tray, said feeding tray comprising a sleeve member removably inserted inwardly of said inlet neck portion and a tray member having an outlet opening therein, and means secured in said tray member and extending through a portion of said sleeve member to detachably connect said sleeve and tray members together and removably engage the recesses adjacent the inlet end of the neck portion to prevent relative rotation of said tray with respect to said neck portion.

8. In a device of the character described, the combination with a food handling apparatus including an inlet neck portion having recesses laterally adjacent thereto, of a feeding tray, said feeding tray comprising a flanged sleeve member removably inserted inwardly of said inlet neck portion and a tray member having an outlet opening therein, and means secured in said tray member and extending through the flange of said sleeve member to detachably connect said sleeve and tray members together and removably engage the recesses adjacent the inlet end of the neck portion to prevent relative rotation of said tray with respect to said neck portion.

SYLVAN BRAUN.
